SIGNALING DEVICE FOR TYPEWRITERS

James V. Payton, Los Angeles, Calif.

Application August 18, 1936, Serial No. 96,631

19 Claims. (Cl. 197—189)

This invention relates to signaling devices for typewriters, of the general character embodied in my U. S. Patent No. 1,945,753, issued February 6, 1934, wherein means is provided to automatically indicate to the typist the proximity of the typing to the hidden lower edge of the sheet being typed.

An object of the present invention is to provide a signaling device which is structurally and functionally characterized to reduce to a negligible minimum such friction as might tend to adversely affect the operation of its working parts, so as to render the mechanism sensitive and absolutely positive and dependable in operation in indicating to the typist the proximity of the typing to the hidden lower edge of the sheet being typed, and in such relation thereto that the last line of the sheet can be safely typed without slipping of the sheet, whereby to enable a neat and uniform lower margin to be attained on all sheets, and full speed typing maintained through the sheet without risk of running off the lower end of the sheet.

Another object of the invention is to provide a signaling device for typewriters which is comparatively simple in construction; is compact so as to be unobtrusive and unobstructive to the normal use of the typewriter, as well as readily adaptable to the typewriter.

With these and other objects in view, the invention consists in the combinations, arrangements and functional relationships of elements as set forth in the following specification and particularly pointed out in the appended claims.

In the accompanying drawing,

Figure 1 shows in vertical longitudinal section a typewriter platen, with several correlated parts of the typewriter, and showing one form of signaling device embodying this invention applied thereto.

Figure 2 is a fragmentary plan view of the signaling device in its association with the platen;

Figures 3 and 4 are transverse sectional views taken, respectively, on the lines 3—3 and 4—4 of Figure 1;

Figure 5 is a transverse sectional view taken on the line 5—5 of Figure 1 and illustrating the position of the signaling device during the typing operation;

Figure 6 is a view similar to Figure 5 but showing a released position of the device;

Figure 7 is a transverse sectional view taken on the line 7—7 of Figure 1;

Figure 8 is a perspective view of a striker embodied in the signal;

Figure 9 is a perspective view of a striker actuating cam;

Figure 10 is a view similar to Figure 6 showing a modified form of paper engaging means.

Referring specifically to the drawing and particularly to Figures 1 to 9, inclusive, a typewriter platen P is fixed to the usual operating shaft 10 journaled in suitable bearings 11—11 provided on the typewriter carriage (not shown), and differs from a conventional platen in that it is slightly reduced in length from its left hand end for the reception of the signaling device in a manner not to obstruct the normal use of the platen.

Firmly seated in an annular recess 12 in the left hand end of the platen is a cup-shaped member 13 forming a pocket adapted to receive a portion of the signaling device, the member having an axial opening through which the shaft 10 projects and has fixed thereto for rotation with the platen an audible signal B in the form of a bell 14 adapted to be sounded by a striker S. The striker comprises a length of spring wire one end of which has fixed thereto a striker head 16. The other end of the wire is in the form of a short coil 17 wound in an annular recess 18 formed in the hub 19 of the bell so as to be frictionally mounted on the hub to rotate with the bell yet enabling the bell to be independently rotated for a purpose to be later described. The portion of the wire adjacent the coil 17 is return bent upon itself at 20 to provide a substantially radial portion 21 which is adapted to be utilized to rock the arm 22 of the striker in a plane substantially parallel to the axis of the shaft 10 about a fulcrum formed by the first convolution of the coil from the portion 21, and to suddenly release the arm to cause the head 16 to strike the bell all in a manner to be later described in conjunction with an energy storing and actuating unit U which is controlled by movements of the platen P and by a sheet of paper extended around the platen as in typing.

The unit U comprises a ring 23 of a diameter to freely fit within the member 13 and is provided with an annular groove 24 receiving a spring 25 undulated longitudinally and normally tending to expand into engagement with the internal annular surface of the member 13 with sufficient force to provide a driving connection between the platen and ring by which the latter is caused to normally rotate with the platen.

A flat coil spring 26 is normally expanded with in the ring 23 and has its outer end fixed in any suitable manner at 27 to the ring. The inner

end of the spring 26 is similarly fixed at 28 to a portion of a hub 29 projecting from one side of a rotary actuator or disk 30 which is of a diameter to be received in the member 13 alongside the ring 23, and is, by means of the hub, mounted to freely rotate on the shaft 10.

The other portion of the hub 29 projects from the opposite side of the disk 30 and has threaded thereon so as to solidly abut a shoulder 31 on the hub, a rotary cam 32 provided with an annular rim 33 projecting from one side thereof and having an inclined camming edge 34 extending through an angle of approximately 90° and adapted to bear against the portion 21 of the 10 striker S. The remaining 270° of the rim 33 constitutes a low dwell surface, and it will be noted that one end of the latter and the high end of the edge 34 are joined by an axially extending shoulder 35 which is adapted to also co-act with 20 the portion 21 of the striker in a manner to be later described.

A control member C forming a part of the unit U comprises a disk 36 having a central opening 37 sufficiently large to freely receive the hub 29 25 between the disk 30 and cam 32 so as to mount the disk 36 for transverse or radial movement relative to the platen shaft 10.

At diametrically opposed points, relatively large wheels 38 and 39 are rotatably mounted on 30 the side of the disk 30 confronting the cam 32. The wheel 38 is straddled by the arms of a yoke 40 projecting from an L-shaped arm 41 the free end of which is secured by a set screw 42 to the conventional paper finger carrying shaft 43 35 which is supported in the bearings 44—44 of the carriage in parallelism with and at the rear of the platen as will be understood by those familiar with the art.

The yoke 40 which is vertically disposed, 40 acts with the wheel 38 and with two diametrically opposed and relatively small rollers 44—44 also on the disk 36, to confine the latter against rotation yet permit transverse or radial movement of the disk.

45 Under the action of gravity, the disk 36 occupies a lowered position shown in Figure 6 wherein the disk is supported clear of the hub 29 by the rollers 44 which rest upon downwardly and outwardly inclined extensions 40a on the lower ends 50 of the arms of the yoke 40. In this lowered position of the disk 36, the wheel 39 which is disposed vertically below the wheel 38, has a portion projecting beyond the periphery of the platen P and freely received in a transverse recess 45 55 formed in the usual sheet deflector D surrounding the lowermost portion of the platen so as to guide a sheet around the latter, as will be understood.

60 Freely mounted intermediate their ends on pins 46—46 at diametrically opposed points on the disk 30 are curved pawls 47—47 which are thus rockably mounted on the disk to occupy under the action of gravity, either an inactive position wherein their heels 48 bear against the 65 hub 29, or an active position wherein their toes 48 bear against the hub and the heels 49 which define substantially radial shoulders on the disk 30, are disposed in the path of movement of a lug 50 projecting from the disk 36, when the 70 latter occupies its raised position shown in full lines in Figures 1 and 7 under the action of a sheet of paper extended around the platen and engaging the wheel 38, all to the end of providing 75 an operative connection between the disks 30

and 36 to temporarily prevent the disk 30 from rotating.

The operation of the invention is as follows:

Prior to the insertion of a sheet of paper, the control member C will occupy the position shown 5 in Figure 6, wherein the paper riding wheel 39 projects downwardly beyond the periphery of the platen in the normal lowered position of the control member C under the action of gravity, and wherein the lug 50 is clear of the path of rotation 10 of the pawls 47 when occupying their active positions as aforesaid.

Upon inserting a sheet of paper and initiating rotation of the platen P to advance the paper, the wheel 39 will coact with the paper to raise 15 the control member C and hence dispose the lug 50 in the path of the heels 49 of the pawls 47 when occupying their active positions. It will be understood that during advancing movement of the platen P, the ring 23 is caused to rotate 20 with the platen because of the frictional driving connection between the ring and platen provided by the undulated spring 26 wrapped around the ring in its groove 24.

Now, as advancing movement of the platen is 25 continued, the first one of the pawls 47 which approaches the lug 50 is rocked by gravity to its active position so that its heel 49 will engage the lug and thus arrest rotation of the disk 30, to thereby initiate winding or loading of the 30 coil spring 26, as it will be remembered that the inner end of this spring is fixed to the hub 29 of the disk 30, and the outer end of the spring is fixed to the ring 23.

As the cam 32 is now also held against rotation, and as the bell B is being rotated by the platen, the portion 21 of the striker S, in riding upon the camming edge 34 towards its low terminal, will engage the shoulder 35 of the cam so as to arrest further rotation of the striker by 40 the bell. It will be appreciated that as continued rotation of the bell under advancing movement of the platen tends to unwind the coil 17 of the striker S in the recess 18 of the bell hub 16, that the hub is free to slip within the coil and thus 45 not restrict such rotation of the bell.

As advancing movement of the platen is continued step by step during the typing operation, the spring 26 is being wound to thus store up 50 energy therein. When the bottom edge of the paper reaches a point below the platen at which the wheel 39 is cleared, the control member C is thus rendered free to gravitate instantly to its lowered position shown in Figure 6, thereby disengaging the lug 50 from that one of the pawls 47 with which it has been co-acting to arrest rotation of the disk 30.

As the disk is now free for rotation, the energy 60 stored in the spring 26 by the winding of the spring during advancing movement of the platen, 65 instantly manifests itself by rotating the disk 30 and hence the cam 32 in the direction corresponding to the advancing movement of the platen, thus causing the shoulder 35 of the cam to leave the portion 21 of the striker S, and the rim 33 of the cam to traverse the portion 21. As the inclined camming edge 34 of the cam traverses the portion 21, the striker arm is stressed laterally so that when the high terminal of the camming edge leaves the portion 21, the striker arm will 70 be suddenly released for the striker head 16 to strike the bell B and thus produce a clearly audible signal to the operator that the last permissible line is being typed.

Should the sheet of paper being typed be ex- 75

ceptionally long, with the result of fully winding the spring 28 during advancing movement of the platen, the spring 25 will yield so as to permit the ring 23 to slip within the cup member 13, thus positively preventing overwinding and breakage of the spring 26.

It is also to be noted that the length of the dwell surface on the cam rim 33 is calculated to insure that notwithstanding the speed of rotation of the cam 32 by the spring 26 when the control member C is tripped, the bell will have been struck before the cam can have made a second revolution to bring the camming edge 34 opposite the portion 21 with the attendant possibility of preventing a signal being given.

It will also be noted that due to the rolling contact provided by the wheels 38 and 39 and rollers 44 with the yoke 40, that the control member C is rendered extremely sensitive, as friction between these parts is reduced to a negligible minimum. Furthermore, the rollers 44 co-act with the downwardly and outwardly inclined extensions 40a to maintain the control member against tilting as a sheet of paper is inserted and strikes the wheel 39, thus facilitating raising of the control member by the paper.

Retrograde movement of the platen can be effected without any harm to the mechanism as the pawls 41 merely rock clear of the lug 50 during such movement of the platen.

By reference to Figure 10, it will be noted that for platens of lesser diameter curved approach members 51-51 can be fixed at 52-52 on the control member C to freely receive the wheel 39 therebetween. The members 51 function to smoothly guide a sheet beneath the wheel during the operation of inserting the sheet from the front or back side of the platen, thus facilitating the insertion of the sheet. In the larger sized platens, the approach members are unnecessary and are dispensed with.

What is claimed is:

1. In a typewriter, a platen; a signal comprising a bell and a striker for sounding the bell; a rotary actuator having means for energizing and releasing the striker to sound the bell in response to rotation of the actuator in one direction; a spring operatively connecting the platen and rotary actuator and adapted to be wound when the platen is rotated to advance a sheet of paper and said actuator is held against rotation; and means controlled by a sheet of paper to prevent rotation of said actuator or free the latter for rotation by the spring according as the paper is extended around the platen or the lower edge of the sheet reaches a predetermined position, whereby to wind the spring during the typing operation and to sound the signal when the sheet has been advanced to the predetermined position.

2. In a typewriter, a platen; a signal comprising a bell and a striker for sounding the bell; a rotary actuator having means for energizing and releasing the striker to sound the bell in response to rotation of the actuator in one direction; a spring operatively connecting the platen and rotary actuator and adapted to be wound when the platen is rotated to advance a sheet of paper and said actuator is held against rotation; means controlled by a sheet of paper to prevent rotation of said actuator or free the latter for rotation by the spring according as the paper is extended around the platen or the lower edge of the sheet reaches a predetermined position, whereby to wind the spring during the typing operation and to sound the signal when the sheet has been

advanced to the predetermined position; and means for preventing overwinding of the spring in the event that the sheet is of such length that the spring has been fully wound before the bottom edge of the sheet reaches the aforesated predetermined position.

3. In a typewriter, a platen; a signal comprising a bell and a striker for sounding the bell; a rotary actuator having means for energizing and releasing the striker to sound the bell in response to rotation of the actuator in one direction; a spring operatively connecting the platen and rotary actuator and adapted to be wound when the platen is rotated to advance a sheet of paper and said actuator is held against rotation; means controlled by a sheet of paper to prevent rotation of the said actuator or free the latter for rotation by the spring according as the paper is extended around the platen or the lower edge of the sheet reaches a predetermined position, whereby to wind the spring during the typing operation and to sound the signal when the sheet has been advanced to the predetermined position; and a frictional driving connection for the spring between the platen and said actuator normally enabling the spring to be wound in response to advancing movement of the platen yet yielding when the spring has been wound to such extent that further winding might cause breaking of the spring.

4. In a typewriter, a platen; a signal comprising a bell and a striker for sounding the bell; a rotary actuator having an annular cam co-acting with the striker to stress and then release the latter for striking of the bell, in response to rotation of the actuator in one direction; a spring operatively connecting the platen and rotary actuator and adapted to be wound when the platen is rotated to advance a sheet of paper and said actuator is held against rotation; a control member mounted for movement transversely of the platen axis to occupy either of two extreme positions; means on the control member adapted to co-act with a sheet of paper when extended around the platen in moving the control member to one extreme position; and co-acting means on the control member and rotary actuator by which rotation of the latter is prevented when the control member occupies said one extreme position, or the actuator released for rotation when the control member occupies its other extreme position, whereby to energize the spring during the typing operation and to sound the signal when the bottom edge of the sheet clears said paper co-acting means.

5. In a typewriter, a platen; a signal comprising a bell and a striker for sounding the bell; a rotary actuator having an annular cam co-acting with the striker to stress and then release the latter for striking of the bell, in response to rotation of the actuator in one direction; a spring operatively connecting the platen and rotary actuator and adapted to be wound when the platen is rotated to advance a sheet of paper and said actuator is held against rotation; a control member mounted for movement transversely of the platen axis to occupy either of two extreme positions; means on the control member adapted to co-act with a sheet of paper when extended around the platen in moving the control member to one extreme position; and co-acting lug and pawl means on the control member and rotary actuator by which rotation of the latter is prevented when the control member occupies said one extreme position, or the actuator released

- for rotation when the control member occupies its other extreme position, whereby to energize the spring during the typing operation and to sound the signal when the bottom edge of the sheet clears said paper co-acting means.
6. In a typewriter, a platen; a signal comprising a bell and a striker for sounding the bell; a rotary actuator having means for energizing and releasing the striker to sound the bell in response to rotation of the actuator in one direction; a spring operatively connecting the platen and rotary actuator and adapted to be wound when the platen is rotated to advance a sheet of paper and said actuator is held against rotation; a control member; means confining the control member against rotation and mounting the latter for vertical movement transversely of the platen axis to normally gravitate to a lowered position; means on the control member adapted to co-act with a sheet of paper when extended around the platen, in moving the control member to a raised position; and co-acting means on the control member and rotary actuator by which rotation of the actuator is prevented or permitted according as the control member occupies raised or lowered position, whereby to wind the spring during the typing operation and to sound the signal when the bottom edge of the sheet clears the paper co-acting means.
7. In a typewriter, a platen; a signal comprising a bell and a striker for sounding the bell; a rotary actuator having means for energizing and releasing the striker to sound the bell in response to rotation of the actuator in one direction; a spring operatively connecting the platen and rotary actuator and adapted to be wound when the platen is rotated to advance a sheet of paper and said actuator is held against rotation; a control member; a wheel on the control member and a fixedly mounted yoke straddling the wheel for co-action therewith in preventing rotation of the control member while mounting the latter for vertical movement transversely of the platen axis to normally gravitate to a lowered position; a paper riding wheel on the control member adapted to co-act with a sheet when extended around the platen, in moving the control member to a raised position; and co-acting means on the control member and rotary actuator by which rotation of the latter is prevented or permitted according as the control member occupies raised or lowered position, whereby the spring will be wound during the typing operation and the signal will be sounded when the bottom edge of the sheet clears the paper riding wheel.
8. In a typewriter, a platen; a signal comprising a bell and a striker for sounding the bell; a rotary actuator having means for energizing and releasing the striker to sound the bell in response to rotation of the actuator in one direction; a spring operatively connecting the platen and rotary actuator and adapted to be wound when the platen is rotated to advance a sheet of paper and said actuator is held against rotation; a control member; a wheel on the control member and a fixedly mounted yoke straddling the wheel for co-action therewith in preventing rotation of the control member while mounting the latter for vertical movement transversely of the platen axis to normally gravitate to a lowered position; a paper riding wheel on the control member adapted to co-act with a sheet when extended around the platen, in moving the control member to a raised position; co-acting means on the control member and rotary actuator by which

rotation of the latter is prevented or permitted according as the control member occupies raised or lowered position, whereby the spring will be wound during the typing operation and the signal will be sounded when the bottom edge of the sheet clears the paper riding wheel; rollers on the control member engaging the arms of said yoke at their outer sides for co-action with the first mentioned wheel in guiding the control member vertically; and means on the yoke co-acting with said rollers to suspend the control member in its lowered position.

9. In a typewriter, a platen; a signal comprising a bell and a striker for sounding the bell; a rotary actuator having means for energizing and releasing the striker to sound the bell in response to rotation of the actuator in one direction; a spring operatively connecting the platen and rotary actuator and adapted to be wound when the platen is rotated to advance a sheet of paper and said actuator is held against rotation; a control member; a wheel on the control member and a fixedly mounted yoke straddling the wheel for co-action therewith in preventing rotation of the control member while mounting the latter for vertical movement transversely of the platen axis to normally gravitate to a lowered position; a paper riding wheel on the control member adapted to co-act with a sheet when extended around the platen, in moving the control member to a raised position; co-acting means on the control member and rotary actuator by which rotation of the latter is prevented or permitted according as the control member occupies raised or lowered position, whereby the spring will be wound during the typing operation and the signal will be sounded when the bottom edge of the sheet clears the paper riding wheel; rollers on the control member engaging the arms of said yoke at their outer sides for co-action with the first mentioned wheel in guiding the control member vertically; and downwardly and outwardly inclined extensions projecting from the yoke arms and on which the rollers ride for co-action therewith in suspending the control member in lowered position and guiding the control member against tilting movement.

10. In a typewriter, a rotatably mounted shaft; a platen fixed to said shaft and having an annular pocket in one end; a bell mounted on the shaft; a striker having a resilient arm and correlated with the bell to strike the latter; a ring mounted in said pocket and having an annular groove; a spring seating in said groove and engaging the wall of said pocket to provide a friction driving connection between the platen and ring; a disk rotatably mounted in the pocket; a coil spring connected to the ring and disk for winding of said spring when the platen is rotated to advance a sheet of paper and said disk is held against rotation; a control member mounted for movement transversely of the platen axis to occupy raised and lowered positions, and having means adapted to co-act with a sheet of paper when extended around the platen, in moving the control member to its raised position; co-acting means on the control member and disk by which rotation of the latter is prevented or permitted according as the control member occupies raised or lowered position; and means on the disk responsive to rotation of the disk under the action of the coil spring, to co-act with the striker arm in stressing and then releasing the latter to strike the bell.

11. In a typewriter, a rotatably mounted shaft; a platen fixed to said shaft and having an annular pocket in one end; a bell mounted on the shaft; a

- striker having a resilient arm and correlated with the bell to strike the latter; a ring mounted in said pocket and having an annular groove; a spring seating in said groove and engaging the 5 wall of said pocket to provide a friction driving connection between the platen and ring; a disk rotatably mounted in the pocket; a coil spring connected to the ring and disk for winding of said spring when the platen is rotated to advance 10 a sheet of paper and said disk is held against rotation; a control member mounted for movement transversely of the platen axis to occupy raised and lowered positions, and having means adapted to co-act with a sheet of paper when 15 extended around the platen, in moving the control member to its raised position; co-acting means on the control member and disk by which rotation of the latter is prevented or permitted according as the control member occupies raised 20 or lowered position; and an annular cam on said disk, bearing against the striker arm to stress and release the latter in response to rotation of the disk under the action of the coil spring, for sounding of the bell by the striker.
- 25 12. In a typewriter, a rotatably mounted shaft; a platen fixed to said shaft and having an annular pocket in one end; a bell mounted on the shaft; a striker having a resilient arm and correlated with the bell to strike the latter; a ring mounted in 30 said pocket and having an annular groove; a spring seating in said groove and engaging the wall of said pocket to provide a friction driving connection between the platen and ring; a disk rotatably mounted in the pocket; a coil spring 35 connected to the ring and disk for winding of said spring when the platen is rotated to advance a sheet of paper and said disk is held against rotation; a control member mounted for movement transversely of the platen axis to occupy raised 40 and lowered positions, and having means adapted to co-act with a sheet of paper when extended around the platen, in moving the control member to its raised position; a lug on the control member and pawls on the disk coacting to prevent or 45 permit rotation of the latter according as the control member occupies raised or lowered position; and means on the disk responsive to rotation of the latter under the action of the coil spring, to co-act with the striker arm in stressing and 50 releasing the latter to strike the bell.
13. In a typewriter, a rotatably mounted shaft; a platen fixed to said shaft and having an annular pocket in one end; a bell mounted on the shaft; a striker having a resilient arm and correlated 55 with the bell to strike the latter; a ring mounted in said pocket and having an annular groove; a spring seating in said groove and engaging the wall of said pocket to provide a friction driving connection between the platen and ring; a disk 60 rotatably mounted in the pocket; a coil spring connected to the ring and disk for winding of said spring when the platen is rotated to advance a sheet of paper and said disk is held against rotation; a control member mounted for movement transversely of the platen axis to occupy 65 raised and lowered positions, and having means adapted to co-act with a sheet of paper when extended around the platen, in moving the control member to its raised position; co-acting 70 means on the control member and disk by which rotation of the latter is prevented or permitted according as the control member occupies raised or lowered position; and means on the disk responsive to rotation of the disk under the action of the coil spring, to co-act with the striker arm 75
- in stressing and then releasing the latter to strike the bell; said bell having a hub by which it is fixed to the shaft; and said striker arm having a portion coiled about the hub to mount the 5 striker thereon yet permit the bell to be rotated with the platen during advancing movement of the latter, without rotating the striker.
14. In a typewriter, a rotatably mounted shaft; a platen fixed to said shaft and having an annular pocket in one end; a bell mounted on the 10 shaft; a striker having a resilient arm and correlated with the bell to strike the latter; a ring mounted in said pocket and having an annular groove; a spring seating in said groove and engaging the wall of said pocket to provide a friction driving connection between the platen and ring; a disk rotatably mounted in the pocket; a coil spring connected to the ring and disk for winding of said spring when the platen is rotated to advance a sheet of paper and said disk is held 15 against rotation; a control disk having a wheel; a fixedly mounted yoke the arms of which straddle said wheel for co-action therewith in mounting the control disk for vertical movement transversely of the platen axis to normally gravitate 20 to a lowered position; a paper riding wheel carried by the control disk and adapted to co-act with a sheet of paper to move the control disk to a raised position; means on the first disk and the control disk co-acting to prevent or permit 25 rotation of the first disk according as the control disk occupies raised or lowered positions; and means on the first disk responsive to rotation of the latter under the action of the coil spring, to coact with the striker arm in stressing and 30 releasing the latter to strike the bell.
15. In a typewriter, a rotatably mounted shaft; a platen fixed to said shaft and having an annular pocket in one end; a bell mounted on the 35 shaft; a striker having a resilient arm and correlated with the bell to strike the latter; a ring mounted in said pocket and having an annular groove; a spring seating in said groove and engaging the wall of said pocket to provide a friction driving connection between the platen and ring; a disk rotatably mounted in the pocket; a coil spring connected to the ring and disk for winding of said spring when the platen is rotated to advance a sheet of paper and said disk is held against rotation; a control disk having a 40 wheel; a fixedly mounted yoke the arms of which straddle said wheel for co-action therewith in mounting the control disk for vertical movement transversely of the platen axis to normally 45 gravitate to a lowered position; a paper riding wheel carried by the control disk and adapted to co-act with a sheet of paper to move the control disk to a raised position; means on the first disk and the control disk co-acting to prevent or permit rotation of the first disk according as the control disk occupies raised or lowered position; 50 means on the first disk responsive to rotation of the latter under the action of the coil spring, to co-act with the striker arm in stressing and releasing the latter to strike the bell; guide rollers 55 on the control disk engaging the yoke arms at the outer sides thereof; and lateral extensions on the yoke arms co-acting with the rollers to suspend the control disk in lowered position.
16. In a typewriter, a platen; a signal; a rotary actuator for activating the signal in response to rotation of the actuator in one direction; means operatively connecting the platen and actuator, and by which energy is stored when the platen is rotated to advance a sheet of paper, 75

and said actuator is held against rotation; and means controlled by the paper to prevent or permit rotation of said actuator by the last means according as the paper is extended around the platen or the lower edge of the sheet reaches a predetermined position, whereby to store energy during the typing operation and to activate the signal when the sheet has been advanced to the aforesaid predetermined position.

10 17. In a typewriter, a platen; a signal; a rotary actuator for activating the signal in response to rotation of the actuator; energy storing means for rotating the actuator; means for holding the actuator against rotation by the first means; means including a paper riding wheel by which the actuator is caused to be released for rotation by the first means when the lower edge of a sheet reaches a predetermined position around the platen, whereby to activate the signal; and approach members freely receiving said wheel therebetween and adapted to smoothly guide a sheet beneath the wheel when inserting the sheet from the front or back of the platen.

18. In a typewriter, a platen; a signal; a rotary actuator for activating the signal in response to rotation of the actuator in one direc-

tion; a spring adapted to be wound to store energy when the actuator is held from rotating during paper advancing movement of the platen; means for holding the actuator against rotation; means for releasing the actuator when the lower edge of a sheet reaches a predetermined position around the platen, whereby to enable the spring to unwind and rotate the actuator so as to activate the signal; and means for preventing overwinding of the spring.

19. In a typewriter, a platen; a signal; a rotary actuator for activating the signal in response to rotation of the actuator in one direction; a spring adapted to be wound to store energy when the actuator is held from rotating during paper advancing movement of the platen; means for holding the actuator against rotation; means for releasing the actuator when the lower edge of a sheet reaches a predetermined position around the platen, whereby to enable the spring to unwind and rotate the actuator so as to activate the signal; and a yieldable driving connection between the platen and actuator operable to prevent overwinding of the spring.

25 JAMES Y. PAYTON.
